GAS BURNER

Filed Jan. 24, 1929

Inventor,
George A. Guenther,
by Worcester P. Geiger
Attorney

UNITED STATES PATENT OFFICE

GEORGE A. GUENTHER, OF BUFFALO, NEW YORK

GAS BURNER

Application filed June 24, 1929. Serial No. 373,078.

This invention relates to improvements in gas burners.

One of its objects is the provision of a burner which is simple, compact and inexpensive in construction, and which can be readily dismembered for cleaning purposes.

Another object of the invention is to provide a gas burner in which the pilot is constructed and arranged to form an integral part of the burner.

In the accompanying drawings:—

Figure 1 is a perspective view of a gas burner embodying my invention. Figure 2 is a vertical longitudinal section thereof on line 2—2, Figure 1. Figure 3 is a transverse section on line 3—3, Figure 4, Figure 4 is a fragmentary vertical section on line 4—4, Figure 3. Figure 5 is a perspective view of one of the burner bars.

Similar characters of reference indicate the corresponding parts throughout the several views.

In its preferred construction, the burner comprises a body 10 of substantially the shape shown in the drawings, having a main gas chamber 11 and an enlargement 12 disposed centrally at the front side of the body and containing an auxiliary or pilot chamber 13. The main chamber has a gas inlet 14 and the pilot chamber has a similar inlet 15, said inlets registering with corresponding gas passages 16, 17 respectively formed in a gas supply pipe 18 upon the upper end of which the lower recessed end 19 of the burner-body 35 is removably seated. As shown in Figures 3 and 4, that portion of the gas pipe containing the passage 17 has a projection 20 at its top which engages a corresponding socket 21 in the burner-body.

The burner-body is open at its top and formed in the marginal edges of its side walls by saw-cuts or otherwise are a series of equally-spaced grooves or recesses 22 in which are removably arranged a plurality of transverse bars or partitions 23 set edge-wise in their grooves and terminating at their ends flush with the outside faces of the burner side walls. These burner-bars form a plurality of narrow jet openings or flame slots 50 24 and they are preferably provided at the

upper corners thereof with notches 25. Angle plates 26 applied to the opposite sides of the burner-body 10 serve to hold the burner-bars 23 in place, the horizontal flanges thereof engaging the notched ends of said burner bars to prevent their displacement both laterally and vertically, and the vertical flanges thereof sealing the open ends of the flame slots.

Said burner-bars 23 extend from the ends 60 of the burner-body to a point opposite the enlargement 12 thereof. Disposed in this resulting space are a series of auxiliary or pilot burner bars 27 which are supported in grooves 28, 29 formed in the central portion 65 of the front wall of the body 10 and in the opposing side wall of the enlargement 12, respectively. These bars, as shown in Figures 1 and 3 are longer than the companion bars 23, extending across the main gas chamber 11 and the pilot chamber 13 to form intercommunicating flame slots 30. The ribs or webs 31 resulting from the grooves 28 in the front wall of the burner-body are preferably shorter in height than the webs between the main bar-grooves 22 so as to provide for the lateral passage or spreading of the pilot-flame into the main gas chamber 11 below the top edges of the auxiliary burner-bars 27, as seen in Figures 2 and 3. A taper pin 32 may be used for holding the several auxiliary burner-bars in place.

I claim as my invention:—

1. A gas burner, comprising a body having a main gas chamber and an adjoining pilot chamber, both of said chambers having their open upper end disposed alongside each other, and burner bars extending across and bridging the open ends of said main chamber, some of said bars being of a length to 85 jointly bridge the main chamber and the pilot chamber to form intercommunicating flame-slots between said chambers.

2. A gas burner, comprising a body having a main gas chamber and an adjoining pilot chamber, said chambers being open at their upper ends and having laterally-aligned recesses in their opposing side walls, and burner-bars removably seated in said recesses, some of said bars being of a length to joint- 100

ly bridge the open ends of said chambers and forming flame-slots therebetween connecting the pilot chamber with the main gas chamber.

3. A gas burner, comprising a burner-body having a main gas chamber and a pilot gas chamber disposed alongside the latter, a plurality of equally-spaced ribs at the top edges of the opposing side walls of said chambers and forming recesses therebetween, and a plurality of burner-bars arranged transversely of said chambers and seated in said recesses to form intervening flame-slots, the ribs formed in that wall between the main chamber and the pilot chamber being shorter than the remaining ones to provide for a lateral passage of the pilot-flame into the main gas chamber.
